UNITED STATES PATENT OFFICE

MAXIMILLIAN C. HAERMAN, OF CLEVELAND, OHIO, ASSIGNOR TO THEO. A. KOCHS COMPANY, OF CHICAGO, ILLINOIS, A CORPORATION OF ILLINOIS

DESIGN FOR A CORNER SIGN

Application filed September 7, 1929. Serial No. 32,690. Term of patent 7 years.

To all whom it may concern:

Be it known that I, MAXIMILLIAN C. HAERMAN, a citizen of the United States, residing at Cleveland, in the county of Cuyahoga and State of Ohio, have invented a new, original, and ornamental Design for a Corner Sign, of which the following is a specification, reference being had to the accompanying drawing, forming part thereof,

The figure is a perspective view of a corner sign showing my new design.

I claim:

The ornamental design for a corner sign, as shown.

M. C. HAERMAN.
